UNITED STATES PATENT OFFICE

BOHUMIL KRAUPNER, OF ROUDNICE, CZECHOSLOVAKIA

PRESSING IRON

Application filed July 11, 1927; Serial No. 204,807, and in Czechoslovakia November 17, 1926.

This invention relates to a pressing iron which by means of a simple handle can be converted into another apparatus, e. g. into a cooking appliance, drying apparatus, frying pan or the like. A further advantage of the invention resides in the fact that the pressing iron has electrical heating means so constructed that, by suitably connecting it up, different temperatures can be obtained with the minimum consumption of current; moreover the cooking appliance or the like can be heated over a smaller or greater area.

One embodiment of the invention will now be described by way of example and with reference to the accompanying drawing, whereon:

Fig. 1 is a section through the pressing iron,

Fig. 2 a view of the heating means from underneath,

Fig. 3 a view of iron converted into a cooking appliance, and

Fig. 4 a rear view of the iron.

According to the invention, the iron comprises two parts. The upper part of the iron has heating means, i. e. an internal body 1, in which is embodied a resistance wire 2, preferably a spiral in grooves 3. The grooves are made in sinuous form. In the heating means is an opening 4, into which an article, e. g. hair curling tongs or the like, can be inserted. The resistance wires can be brought to a red heat through the medium of the terminals 5, 6 and 7, the terminals 5 and 6 being at the ends of the coils (Fig. 2), while the terminal 7 is located between the ends thereof.

As already mentioned, the heating means is disposed in the upper part 1 of the iron 40 8, which part fits into the lower part 9 in such a way that both parts are held together at the forward end by the exterior surface 10 (Fig. 1) engaging with the inclined surface 11 on the interior of the lower part. By 45 tightening up the screw 12 the upper part 8 is pressed forward so that the inclined surfaces 10 and 11 contact and the upper part cannot become disengaged.

The handle 13 of the iron serves also as a 50 handle for the cooking or other appliance

into which the iron can be converted, for it is pivoted about the pin 15 by means of the cranked part 14 and is firmly held by the screw 16.

The iron is provided with a plate 17 which 55 protects the hand from excessive heat and further serves as a base for the cooking appliance, as shown in Fig. 3 wherein the lower part 9 has been removed. In order to obtain a lighter construction, a plate of semi-circular form secured in position by means of screws 19 forms the rear of the iron and has an opening 20 concentric with the opening 4 in the heating means.

By the arrangement of the resistance wires 65 in sinuous form in conjunction with the arrangement of terminals described, numerous technical advantages are obtained, for these make it possible to heat up the internal body over a small, limited central area by making 70 electrical connection through the terminals 5 and 7, or over the whole area by making connection through the terminals 7, 6, 5, which is desirable in using the iron as a cooking 75 appliance. Again, the internal body can be raised to a low temperature, for example, for ironing purposes, by making series connection through the terminals 6 and 5 or to a high temperature for cooking purposes by making connection in parallel through the 80 terminals 7, 6, 5, all these arrangements being obtainable by the mere manipulation of a switch.

The upper part 1 of the iron is so made 85 that different kinds of heating means may be provided. For example, instead of the above described electrical arrangement, the sinuous resistance may be removed and gas, spirit, petrol or like means provided.

I claim:

1. A pressing iron comprising a lower part provided with a flat surface, a rim on said lower part having an inclined interior surface, a body part provided with internal heating means, an inclined exterior surface 95 on said body part adapted to be engaged by the inclined surface on the lower part, screw means for holding said inclined surfaces removably in engagement to hold the two parts together, a plate on the upper surface of the 100

body part upon which the iron can stand when inverted, and a handle movably mounted on the body part to serve in one position as a handle when ironing and in another position as a handle for the iron when used as a heating appliance otherwise than for ironing.

2. A pressing iron comprising a lower part provided with a flat surface, a body part, means for removably securing the two parts together, a heating element in the body part provided with an opening for the insertion of an article to be heated, a corresponding opening in the wall of the body part, and a handle movably mounted on the body part to serve in one position as a handle when ironing and in another position as a handle for the iron when used as a heating appliance otherwise than for ironing.

3. A pressing iron comprising a lower part provided with a flat surface, a body part, means for removably securing the two parts together, a sinuous length of resistance wire in the body part, a terminal at each end thereof, a terminal between the ends thereof so that the extent of the area heated and the intensity of the heating can be varied, and a handle movably mounted on the body part to serve in one position as a handle when ironing and in another position as a handle for the iron when used as a heating appliance otherwise than for ironing.

4. A pressing iron comprising a lower part provided with a flat surface, a body part, a rim on said lower part having an inclined interior surface, an inclined exterior surface on said body part adapted to be engaged by the inclined surface on the lower part, screw-means for holding said inclined surfaces removably in engagement, a heating element in the body part provided with an opening for the insertion of an article to be heated, a corresponding opening in the wall of the body part, a sinuous length of resistance wire in grooves in said heating element, a terminal at each end thereof, a plate on the upper surface of the body part upon which the iron can stand when inverted, and a handle movably mounted on the body part to serve in one position as a handle when ironing and in another position as a handle for the iron when used as a heating appliance otherwise than for ironing.

5. In testimony whereof I affix my signature.
BOHUMIL KRAUPNER.
